UNITED STATES PATENT OFFICE.

SAMUEL HARARY, OF BROOKLYN, NEW YORK.

METHOD FOR PREPARING BUCKRAM.

No Drawing.

Application filed January 20, 1928. Serial No. 248,278.

This invention relates generally to the art of embroidering, and has more particular reference to a method of preparing pattern material for the embroidery trade capable 5 of being readily disintegrated by the application of heat of such temperature that will not adversely affect the main material to be embroidered.

The invention has for an object the provision of a method of the class mentioned, that is highly efficient and desirable, and by which pattern material as specified, may be manufactured at a low cost.

The invention has for a further object, the provision of a pattern material of the said type, which does not disintegrate at normal room conditions as fast as similar material made from other materials and old methods.

For further comprehension of the invention, and of the objects and advantages thereof, reference will be had to the following description and to the appended claims in which the various novel features of the invention are more particularly set forth.

The method first makes use of glue sized material such as cotton, linen, hemp or pulp fabrics treated with starch or glue. More specifically stated, commercial buckram may be used though the invention is not limited 30 to the sole use of this material. Paper or other fiber products may also be used instead of buckram, muriatic acid and water are the other elements necessary to carry out the method.

So that others may make use of my invention, I give the following as one of the most approved formulas for carrying the same out.

Place in any suitable vessel a mixture of 40 60 gallons of water, and 4 to 48 pounds of muriatic acid, preferably 12 pounds will be sufficient. The mixture should be at room or lower temperature, approximately from 68° F. to 33° F. and then saturate starched 45 material, preferably buckram therein. Remove the material and allow it to dry, either naturally or by means of a slightly heated conveyor.

Pattern material thus prepared will keep 50 in good condition for a much longer period of time, than material prepared by old methods. A great drawback to the manufacture and sale of pattern material is that after several days the acid within the material 55 ruins the material and necessitates the discarding of the ruined material and makes it

impossible to ship the treated material to distant embroiderers. This forms a bar to the stocking of the material in the trade.

Material made according to the instant 60 disclosure lasts approximately twenty times as long as material made according to old methods. Obviously this is a great advantage in the embroidery trade.

Pattern material of the class mentioned 65 has several uses in the embroidery trade. One use consists in designing the pattern material, then basting the same to material to be embroidered. Embroidering is next done according to the pattern thru both materials. Upon completion a hot iron is applied to the materials or the material is placed in a hot room and the pattern material disintegrates at a temperature of about 70 170° which temperature does not affect the 75 main material, and the charred pattern material may be readily removed.

In material made in accordance with the present invention, the acid resist protects the fabric from the action of the acid for an 80 extended period of time at normal atmospheric temperatures, as the reaction between the acid and the resist is very slow. Upon application of heat to the material, however, the acid reaction is greatly accelerated 85 and both the acid resist and fabric are rapidly disintegrated.

While I have described my invention with some degree of particularity, I realize that in practice various alterations therein may 90 be made. I therefore reserve the right and privilege of changing the form of the details of construction or otherwise altering the arrangement of the correlated parts without departing from the spirit or the 95 scope of the appended claims.

Having thus described my invention what I claim as new and desire to secure by United States Letters Patent is:

1. A process for preparing pattern material for embroidery purposes, comprising the step of sizing fabric material with an acid resist, saturating the sized material with diluted muriatic acid, and then drying the acid saturated material. 100 105

2. A process for preparing pattern material for embroidery purposes, comprising the step of sizing fabric material with starch, saturating the sized material in a diluted acid, and then allowing the acid saturated material to dry in the atmosphere at substantially atmospheric temperatures. 110

3. As an article of manufacture, a dry pattern adapted for use in embroidering, comprising fabric material, sizing thereon, and acid on said sizing, said acid being slow acting at atmospheric temperatures, said acid being adapted to rapidly disintegrate the sizing and fabric at a temperature of substantially 170° F.

4. As an article of manufacture, dry pattern material adapted for use in embroider-

ing, comprising fabric material, sizing thereon, muriatic acid on said sizing, said acid being slow acting at atmospheric temperatures, said acid being adapted to rapidly disintegrate the sizing and fabric at a temperature of substantially 170° F. 15

In testimony whereof I have affixed my signature.

SAMUEL HARARY.
